H. E. COX.
COUPLING FOR ROTARY PIPES.
APPLICATION FILED JUNE 20, 1921.

Patented Oct. 10, 1922.

BY

Inventor

Hazard & Miller

UNITED STATES PATENT OFFICE.

HENRY E. COX, OF BREA, CALIFORNIA.

COUPLING FOR ROTARY PIPES.

Application filed June 20, 1921. Serial No. 478,981.

To all whom it may concern:

Be it known that I, HENRY ERWIN Cox, a citizen of the United States, residing at Brea, in the county of Orange and State of California, have invented new and useful Improvements in Couplings for Rotary Pipes, of which the following is a specification.

My invention relates generally to well drilling apparatus and more particularly to a coupling for the tube or pipe sections that extend downwardly into the well and carry the drill or bit, the principal objects of my invention being to generally improve upon and simplify the construction of the existing types of rotary pipe couplings, to provide a construction that is relatively simple, capable of being easily and cheaply produced and which is quick-acting in its coupling and uncoupling functions.

Further objects of my invention are to provide a strong, durable and efficient coupling for rotary pipes and to construct the same so that when in use it will be effective in saving much of the time and labor that is ordinarily involved in connecting and disconnecting rotary pipes such as are utilized in connection with well drilling apparatus.

With the foregoing and other objects in view, my invention consists in certain novel features of construction and arrangement of parts that will be hereinafter more fully described and claimed, and illustrated in the accompanying drawings, in which:

Fig. 1 is a vertical section taken through the center of a coupling of my improved construction and with the parts thereof disconnected.

Fig. 2 is a vertical section taken through the center of the coupling and showing the parts thereof in assembled or connected position.

Fig. 3 is a vertical section similar to Fig. 2 and showing the coupling nipple in vertical section.

Fig. 4 is a horizontal section taken approximately on the line 4—4 of Fig. 1.

Fig. 5 is a cross section taken approximately on the line 5—5 of Fig. 2.

Fig. 6 is a vertical section taken on the line 6—6 of Fig. 1.

Referring by numerals to the accompanying drawings, which illustrate a practical embodiment of my invention, 10—10 designate the adjacent end portions of a pair of pipe or tube sections of the type ordinarily

employed in well drilling apparatus and which are adapted to be detachably connected by my improved coupling, and in order to receive the parts of said coupling, 60 the end portions of these tube or pipe sections are externally threaded.

Secured to the threaded end of the upper pipe or tube section is the internally threaded upper portion of a cap 11, the lower portion thereof being provided with an axially disposed threaded aperture 12, and seated therein is the externally threaded body portion of a tubular member or nipple 13 to the upper end of which is secured, in 70 any suitable manner, a collar 14.

The length of nipple 13 is such that its lower portion projects a substantial distance below the underside of cap 11, and formed integral with the lower end of said nipple is 75 a substantially rectangular horizontally disposed body 16, through which is formed an opening that coincides with the opening through the nipple, and the end portions 17 of the body 16 project beyond the body of 80 said nipple to form ears or lugs that are adapted to engage the cap that is positioned on the end of the adjacent pipe or tube section and the upper faces of said lugs or ears are slightly rounded as designated by 18. 85

A cap 19 has its lower portion internally threaded in order to receive the externally threaded upper end of the lower one of the pipe or tube sections 10, and formed through the upper portion of said cap 19 is a substantially rectangular opening 20, of such size as to permit the free passage through of the head or body 16 on the lower end of nipple 13.

Formed within the cap 19 and to the sides 95 of the rectangular opening therethrough, are horizontally disposed notches or recesses 21, and one end of each of said notches terminates in a vertically disposed shoulder 22 that serves as a stop to limit the rotary 100 movement of the head or block 16, and to position the same transversely with respect or at right angles to the opening 20, in the upper portion of the cap.

Formed in the body of the cap 19, above 105 the end portions of the recesses 21 and immediately adjacent to the shoulders 22 at the ends thereof, are curved or concave seats 23 against which the curved or convex upper faces 18 of the ears or lugs 17 are adapted to 110 engage when the parts of the device are properly coupled.

To unite a pair of tube or pipe sections that are equipped with my improved coupling, the nipple 13 is screwed downwardly in cap 11 until the underside of collar 14 5 bears on the upper surface of the body of said cap. The projecting portion of the nipple and the head or body portion 16 thereon are now inserted through the rectangular opening 20 in the upper portion of 10 cap 19, and one pipe section or the other is rotated approximately a quarter of a turn, with the result that an oppositely disposed pair of side faces of the ears or lugs 17 will be brought to bear against the shoulders 22 at the ends of the recesses 21, and, 15 with the parts thus positioned, the head or block 16 is arranged substantially at right angles to the opening 20.

One pipe section or the other is now rotated one or two complete turns, or until 20 the underface of cap 11 bears directly upon the upper face of cap 19, and such action moves the nipple 13 a short distance upwardly through the cap 11 so that the convex or curved upper faces 18 of lugs or 25 ears 17 will engage the concave seats 23 formed at the ends of recesses 21, and, when the nipple has been thus screwed upwardly to its limit of movement, the parts of the 30 coupling will be very rigidly connected, and a strong and substantial connection between the adjacent pipe sections is accomplished.

Obviously a reversal of the operations just 35 described will position the parts so that they may be readily disconnected.

A pipe coupling of my improved construction is comparatively simple, may be easily and cheaply produced, provides a 40 strong and substantial connection between the end portions of rotary pipes or tubes and particularly those utilized in connection with well drilling apparatus, and the use of the coupling effects a material saving in the time and labor ordinarily involved in 45 coupling or uncoupling pipe or tube sections.

It will be readily understood that minor 50 changes in the size, form and construction of the various parts of my improved pipe coupling may be made and substituted for those herein shown and described without departing from the spirit of my invention, the scope of which is set forth in the appended claims.

I claim as my invention:

55 1. A pipe coupling comprising pipe engaging members, a nipple screw seated in one of said members, the outer end portion of said nipple being provided with lateral projections and the other pipe engaging 60 member being provided with recesses that are adapted to receive the projections on said nipple.

2. In a pipe coupling, a pair of pipe engaging members, a nipple screw seated in one of said members, means for limiting the 65 outward movement of said nipple through the member in which it is seated, lateral projections on the outer portion of the nipple, and the other pipe engaging member being provided with internally arranged recesses 70 that are adapted to receive the lateral projections on said nipple.

3. In a pipe coupling, a pair of pipe engaging members, a nipple screw seated in one of said members, laterally projecting 75 lugs on the outer portion of said nipple, the other pipe engaging member being provided with an opening adapted to receive the projecting portion of the nipple and the lugs thereon, and said last mentioned 80 pipe engaging member being provided with recesses that are adapted to receive the lugs on the nipple.

4. In a pipe coupling, a pair of pipe engaging members, a nipple screw seated in 85 one of said members, means for limiting the movement of said nipple outwardly through the member in which it is seated, the other pipe engaging member being provided with an opening that is adapted to receive the projecting portion of the nipple, and said last mentioned pipe engaging member and the projecting end portion of the 90 nipple being provided with interengaging parts for limiting the rotary movement of 95 the nipple with respect to said last mentioned pipe engaging member and for retaining the parts in assembled relation.

5. A pipe coupling comprising a pair of pipe engaging members, one of which is 100 provided with an opening and with internally arranged recesses to the sides of said opening, a nipple seated in and projecting from the other pipe engaging member, and lugs projecting from the end of said nipple 105 and engaging in said recesses when the parts of the coupling are properly assembled.

6. A pipe coupling comprising a pair of pipe engaging members, one of which is 110 provided with an opening and with internally arranged recesses to the sides of said opening, a nipple seated in and projecting from the other pipe engaging member, lugs projecting from the end of said nipple and 115 engaging in said recesses when the parts of the coupling are properly assembled, and there being shoulders formed at the ends of said recesses for limiting the rotary movement of the nipple with respect to the cap that is provided with the opening and recesses.

In testimony whereof I have signed my name to this specification.

H. E. COX.
